UNITED STATES PATENT OFFICE.

HENRY PAAR, OF CANTON, OHIO, ASSIGNOR TO JOHN L. ARNOLD, OF SAME PLACE.

DESIGN FOR A HORSESHOE-FRAME.

SPECIFICATION forming part of Design No. 32,174, dated January 30, 1900.

Application filed December 30, 1899. Serial No. 742,156. Term of patent 14 years.

To all whom it may concern:

Be it known that I, HENRY PAAR, a citizen of the United States, residing at Canton, in the county of Stark and State of Ohio, have

5 invented and produced a new and original Design for a Horseshoe-Frame, of which the following is a specification, reference being had to the accompanying drawings, forming a part thereof.

10 Figure 1 is a plan view of a horseshoe-frame, showing my new design; and Fig. 2 is a rear view of the same.

15 As shown in the drawings, the leading or material feature of my design consists of a flat horseshoe-shaped bar A, which has parallel top and bottom surfaces and which is

considerably wider than it is thick, and its rear ends *a* are bent inward and forward into a **U** shape, said bent ends being considerably narrower than the body of said bar. 20

Having described my invention, what I claim as new, and desire to secure by Letters Patent, is—

The design for a horseshoe-frame as herein shown and described. 25

In testimony whereof I hereunto affix my signature in the presence of two witnesses.

HENRY PAAR.

Witnesses:

J. A. JEFFERS,
J. R. BOND.
